United States Patent Office

Des. 181,315
Patented Oct. 29, 1957

181,315

INSTRUMENT CONTROL DIAL UNIT

Lawrence R. Rockwood, Oswego, Oreg., assignor to Electro-Measurements, Inc., Portland, Oreg., a corporation of Oregon

Application January 27, 1956, Serial No. 39,947

Term of patent 14 years
(Cl. D26—13)

Fig. 1.

Fig. 2.

Figure 1 is a perspective view of an instrument control dial unit, showing my new design. The undisclosed portions are like those shown; and

Figure 2 is a view in side elevation of the instrument control dial unit shown in Figure 1.

I claim:

The ornamental design for an instrument control dial unit, as shown and described.
